UNITED STATES PATENT OFFICE.

THOMAS M. BARNA, OF ATLANTA, GEORGIA.

COTTON-PLANTER.

SPECIFICATION forming part of Letters Patent No. 270,369, dated January 9, 1883.

Application filed July 17, 1882. (No model.)

To all whom it may concern:

Be it known that I, THOMAS M. BARNA, of Atlanta, in the county of Fulton and State of Georgia, have invented certain new and useful Improvements in Cotton-Planters; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a cotton-planter embodying my improvements. Fig. 2 is a perspective detail view of the furrow-opener and soil-leveler with its roller. Fig. 3 is a sectional view of the latter with its standard. Fig. 4 is a detail view of the covering-disks and their appurtenances. Fig. 5 is a sectional detail view of one end of the central axle which supports the rolling hopper and its bearing in the frame, and Fig. 6 is a vertical cross-section through the front roller and its standard.

Similar letters of reference indicate corresponding parts in all the figures.

My invention has relation to cotton-planters or cotton-seed drills of the class having rotary hoppers; and it consists in certain improvements upon the machine for which Letters Patent of the United States No. 216,548 were granted to me on the 17th day of June, 1879.

The first part of my improvement has relation to the device for opening the furrow which is to receive the seed, and the second part to the means employed for covering the seed after it has been deposited in the furrow. I have further improved the means for hanging the rotary hopper in its frame in such a manner as to insure its perfect operation at all times and under all circumstances.

In the accompanying two sheets of drawings, the letter A represents the frame; B, the tongue, and C C the handles.

D is the rotary hopper, which may be of any approved construction; but I prefer a construction substantially like that shown and described in my Patent No. 216,548, with the difference that I make the hopper cylindrical instead of barrel-shaped, and of sheet metal instead of wood.

E E are the wheels, which are integral with the heads of the hopper.

To the under side of the tongue is bolted the combined furrow-opener and soil-leveler, 55 which is in the nature of a plow having a triangular downwardly-projecting point or share, F, and two sweeps, G G, extending rearwardly in an oblique direction from the base of the share, so as to project beyond or overlap the 60 wheels. Back of this device is a standard, H, bolted to the rearwardly-extended part of the tongue, and having a series of three or more holes in its lower end for the insertion of the bolt h, upon which the roller I revolves. The 65 latter is of the shape shown in cross-section in Fig. 6, it having a V-shaped periphery with slightly-rounded sides. As the machine advances over the ground the triangular share F will open a triangular furrow, the excavated 70 soil from which is swept to both sides and smoothed or leveled by the oblique sweeps G G, and the roller I, entering the furrow immediately back of the opener, operates to slightly compress its sides, so as to prevent its filling 75 up until after the seed has been deposited. Roller I may be adjusted up or down in its standard H to fit any depth of furrow made by the opener.

In the rear part of the frame, back of the 80 axle a, is hung a frame consisting of two side pieces, J J, connected at their outer ends by a curved cross-bar, K.

L and L are the concave rotary covering-disks, which are hung obliquely upon cross-bar K, so as to approach each other at their rear ends and form a wedge-shaped space or opening between them.

M is a roller, which is hung in arms m, pivoted in the outer ends of the side pieces, J, and bearing against lips or projections j, which control the downward play of the roller-arms m and of the roller. This covering device may be raised or lowered by a rod, n, which works through a staple on the upper cross-bar of the 95 handles, and may be held in place by a pin projecting through a hole in the bar. At the lower ends of the handles, where these are connected to the frame A, are adjustable scrapers N, for freeing the wheels from dirt that may 100 adhere to them in working the machine in clay or sticky soil.

Between the boxes A' of frame A, in which the axle *a* of the rotary hopper is journaled, and the disks or wheels E, is placed on each side a movable hub, made in two parts, O and O', as shown more clearly in Fig. 5 of the drawings, each of which has an inwardly-projecting tongue, *o* and *o'*, adapted to fit in grooves or notches *a'* in the square part of the axle. The halves O and O' are held together by a stout wire or circular spring, P, sprung around them. By this means lateral motion of the hopper is obviated, and it will at all times run perfectly true between its boxes or bearings; nor are there any nuts or 15 tightening-bolts which are apt to work loose and get lost.

By the construction and arrangement of the concave rotary covering-disks L L, mounted obliquely upon bar K, in conjunction with the 20 adjustable roller M, the soil is built up over the seed deposited in the furrow and compressed so as to effectually cover and protect it.

Having thus described my invention, I claim and desire to secure by Letters Patent of the 25 United States—

1. In a cotton-planter, the combination, with a rotary hopper, of the furrow-opener consist-

ing of the downwardly-projecting triangular share F, having the flaring oblique sweeps G G, extending rearwardly beyond the wheels of 30 the hopper, and vertically-adjustable roller I, adapted to compress the sides of the furrow made by the opener, and of the covering device consisting of the hinged frame J, cross-bar K, concave disks L L, journaled obliquely 35 upon said cross-bar, and roller M, all constructed and arranged substantially as shown and described, for the purpose set forth.

2. In a cotton-planter, the combination of a rotary hopper, D, having axle *a*, notched or 40 grooved at *a'* and *a'*, frame A, having journal-boxes A', removable hub consisting of the halves O and O', having tongues *o* and *o'* at their inner ends, and annular spring P, constructed and combined to operate substantially as and for the purpose shown and described.

In testimony that I claim the foregoing as my own I have hereunto affixed my signature in presence of two witnesses.

THOMAS M. BARNA.

Witnesses:

AUGUST PETERSON,
J. F. REILY.
